UNITED STATES PATENT OFFICE.

EDWARD A. ALLEN, OF RUMFORD FALLS, MAINE, AND HUGH K. MOORE, OF LYNN, MASSACHUSETTS, ASSIGNORS, BY MESNE ASSIGNMENTS, TO MOORE ELECTROLYTIC COMPANY, OF PORTLAND, MAINE, AND BOSTON, MASSACHUSETTS.

ELECTROLYZING SALTS OF ALKALI METALS.

SPECIFICATION forming part of Letters Patent No. 680,191, dated August 6, 1901.

Application filed October 22, 1897. Serial No. 656,054. (No specimens.)

To all whom it may concern:

Be it known that we, EDWARD A. ALLEN, of Rumford Falls, in the county of Oxford and State of Maine, and HUGH K. MOORE, of Lynn, in the county of Essex and State of Massachusetts, have invented certain new and useful Improvements in Methods of Electrolyzing Salts of Alkali Metals, of which the following is a specification.

10 This invention has relation to processes for the electrolysis of the salts of alkali metals, its object being to provide a process by means of which the electrolyte may be decomposed and the ionic productions carried off without 15 diffusion of the ions given off at one electrode toward the other electrode.

Reference is to be had to the accompanying drawings, and to the letters marked thereon, forming a part of this specification, the same 20 letters designating the same parts or features, as the case may be, wherever they occur.

Of the drawings, Figure 1 represents in vertical sectional view a cell embodying our invention. Fig. 2 represents what we term an 25 automatic "doser"—that is, the device for maintaining the solution in the cell at the proper level. Fig. 3 represents a detailed view of the grid.

Referring to the drawings, *a* indicates the 30 cell, which may be constructed of iron and provided with a lining *a'* of porcelain, clay, any of the halogen derivatives or substitutional products of benzin, (and preferably the chlorin substitutional products,) or graphite; or, if desired, the cell may be constructed of clay or any other substance, provided 35 it or the lining be proof against the attack of chlorin. As shown, it is provided with a cover or dome *a²*, luted upon the top thereof and provided with an escape-duct *a³* for the chlorin, this dome and duct being likewise lined with a substance to prevent its being attacked by the chlorin. The duct may be formed of lead, if desired, which, as known, 40 is proof against chlorin; but if it be formed of iron it is coated or lined in its interior with any one of the substances mentioned above. The lower end of the cell is flanged

and is closed by a diaphragm *b*, of asbestos paper or asbestos cloth, or both, there being 50 a suitable insulation (indicated at *b'*) between the asbestos cloth and the body of the cell, the bolts which secure the diaphragm in place being also insulated from the cell. The diaphragm being of asbestos is sufficiently 55 porous to permit the percolation of a considerable quantity of the liquid therethrough for a purpose to be described. The cell and the diaphragm rest upon an iron grid *c*, there being between the grid and the diaphragm a 60 layer *d* of wire-sponge—that is, a number of layers of wire-cloth—or else a layer formed of iron turnings or borings, matted more or less closely together, to prevent the too-easy 65 percolation or flow of the caustic soda in solution, which is the product of the electrolysis. The cathode being formed in this way is adapted to be saturated with liquid and to hold a considerable body thereof in its pores by capillary action. 70

The grid *c* is provided with legs or standards *d'* to support it upon a deflecting-plate *e*, which is arranged or placed at an angle to conduct the caustic liquid to an outlet-pipe, through which it flows into a suitable tank 75 or receptacle, (indicated at *g*.)

Within the cell is placed a quantity of broken carbon or graphite, which partially fills the cell, this carbon or graphite constituting the anode or positive electrode or the 80 current. The negative electrode or cathode comprises the wire-sponge and, if desired, the grid and the deflecting-plate, provided one end of the line through which the current passes is attached to the said plate. The 85 other end of the line is electrically connected with the anode in any desired way, as through the body of the cell, or else it may be connected with a rod of graphite, carbon, or other suitable material extending down into 90 the anode. The generator of electricity is indicated conventionally at *h*, as are the wires or lines *h' h²*. Leading into the cell, so as to discharge therein a saturated solution of sodium chlorid or any chlorid of an alkali 95 metal at substantially the plane of the top of

the anode, is a glass tube or duct *i*, leading from a receptacle, (indicated at *j*.) This receptacle consists, preferably, of a pipe leading from a tank *k*, in which the solution is discharged from an elevated reservoir *k'*. A float-valve is indicated conventionally at *k*³ and maintains the liquid at the same level in the tank and determines the level of the liquid in the various cells which communicate 10 with the tank by the tubes *i*.

When the anode is immersed in the saturated solution of salt and a current of electricity is turned on the line, the said solution percolates through the diaphragm in 15 considerable quantities and comes into contact with the cathode, in the pores of which it is held by capillary action, and electrolysis instantly begins. Chlorin is liberated at the anode and is conducted away through the 20 duct which leads from the dome, and sodium is deposited at the cathode and is converted into hydrate by the water of the solution which has passed through the diaphragm, the electrolysis of said solution being continued 25 in the cathode until the liquid is dropped through the grid onto the tray. By reason of the cathode not being immersed in the solution, but being located below the diaphragm, there is no chance of the caustic solution 30 diffusing itself through the electrolyte to cause the formation of carbon dioxide by the oxidation of the anode by hypochlorites produced from the hydrate. On the contrary, the cathion or hydrate solution 35 drops from the cathode upon the tray and is conducted away.

The reaction, when the cathode is of iron borings or filings and the electrolyte is a solution of sodium chlorid, is as follows:

We do not confine our process or the use of the cell to the manufacture of caustic soda, as it and the process may be employed for 45 other products, if desired, and consequently where we refer in the claims to "sodium salt" and "sodium hydrate" we mean to include their chemical equivalents.

In cells of this class as heretofore constructed the diaphragm generally is immersed in a tank containing the chlorid solution, whereby the cathode is necessarily immersed in the saline solution also, so that the diffusion of the caustic soda through the 55 diaphragm or porous sides of the cell into the electrolyte therein causes the formation of carbonic-acid gas therein, which impoverishes and dilutes the chlorin, whereas in our cell the cathode is not immersed in the saline solution, and therefore the caustic liquid cannot diffuse itself through the electrolyte in the cell, but passes directly on to the deflecting-plate and the formation of carbonic-acid gas is practically obviated. This is of great 60 importance, especially when the cell is employed in forming a bleaching material by conducting the chlorin over slaked lime,

since the lime has a great affinity for carbonic-acid gas and takes it up rather than the chlorin, thereby causing the character or 70 standard of the bleach to become greatly deteriorated.

We do not herein claim the cell which we have thus illustrated and described, as it forms the subject-matter of divisional application, Serial No. 14,784, filed April 30, 1900, nor do we herein claim the method or apparatus set forth and claimed in our applications, Serial No. 700,337, filed December 27, 1898, and Serial No. 6,480, filed February 26, 80 1900.

Having thus explained the nature of the invention and described a way of constructing and using the same, although without attempting to set forth all of the forms in which 85 it may be made or all of the modes of its use, we declare that what we claim is—

1. The process of producing hydrate from sodium salt, consisting in bringing a solution of said salt in contact with one face of a non-conducting diaphragm of sufficient porosity to readily permit percolation, passing an electric current through said solution and diaphragm into an unimmersed cathode, causing the undecomposed solution to pass through 95 said diaphragm thereby depositing metallic sodium in the cathode, converting the sodium into hydrate by the water of the solution which passed through the diaphragm and washing the hydrate from the cathode by water of the 100 percolated solution.

2. The process of producing hydrate from a solution of sodium salt, consisting in placing said solution in contact with one face of a non-conducting diaphragm of sufficient porosity to readily permit percolation, passing 105 an electric current through said solution and diaphragm into an unimmersed cathode, causing the undecomposed solution to pass through said diaphragm, thereby depositing metallic sodium in the cathode, converting the sodium into hydrate by the water of the solution which 110 passed through the diaphragm and washing the hydrate from the cathode by water of the percolated solution.

3. The process of producing hydrate from a solution of sodium or potassium salt consisting in placing said sodium or potassium solution in contact with one face of a non-conducting diaphragm of sufficient porosity to readily permit percolation, passing an electric current through the solution and diaphragm into an unsubmerged cathode in contact with the outer face of said diaphragm, 120 said cathode being a porous layer of such thickness as to retain a considerable body of liquid in its pores, by capillary action, thereby in the first instance depositing metallic sodium or potassium in the cathode, causing the undecomposed portions of the solution to 125 pass through said diaphragm and by the wa-

130

ter contained therein converting the sodium or potassium previously deposited in the cathode into hydrate and completing the electrolytic decomposition of such sodium or potassium salt as has passed through said diaphragm.

4. The herein-described process for producing hydrate from sodium or potassium chlorid, consisting in bringing an undecomposed aqueous solution of such chlorid into contact with one face of a non-conducting diaphragm of sufficient porosity to readily permit percolation, passing an electric current through said solution and diaphragm into an unimmersed metallic cathode which holds by capillary attraction a considerable quantity of the said solution, whereby there is deposited in said cathode metallic potassium or sodium, converting said metallic potassium or sodium into hydrate by the water of the undecomposed solution in the cathode, and continuously completing in the pores of the cathode the electrolytic decomposition of the said chlorid solution and the hydration of the metal which results therefrom until the hydrate solution is greater than the capacity of

the cathode to hold it by capillary action, whereby said hydrate solution flows by gravity from said cathode.

5. The process of producing the hydrate from the salt of an alkaline metal, consisting in continuously filtering a solution of said salt through a permeable non-conducting diaphragm into the capillary pores of a spongy cathode; passing a current of electricity through said solution and diaphragm to said cathode; continuously washing away the hydrate by the passage of the filtered liquid through the cathode, and removing the hydrate and filtered solution from the cell simultaneously with its removal from the cathode.

In testimony whereof we have signed our names to this specification, in the presence of two subscribing witnesses, this 18th day of October, A. D. 1897.

EDWARD A. ALLEN.
HUGH K. MOORE.
